DEVICE FOR SHUNTING VEHICLES OFF A MAIN LINE OF TRACK

Filed Nov. 19, 1929

UNITED STATES PATENT OFFICE

AUGUSTE SCHEUCHZER, OF RENENS, SWITZERLAND

DEVICE FOR SHUNTING VEHICLES OFF A MAIN LINE OF TRACK

Application filed November 19, 1929, Serial No. 408,200, and in France December 26, 1928.

This invention relates to a device for shunting a vehicle off a main line of track.

The maintenance of railway tracks necessitates the use of various machines such for example as machines for screening ballasts which travel and work on the line of track and may thus interfere with the circulation of the trains. In order to remove this objection, the object of the invention is to provide a device permitting a vehicle to be shunted off a main line of track.

Figures 1 to 3 in the accompanying drawing show by way of example one form of construction of the invention.

15 Figure 1 is a transverse view in elevation of the device.

Figure 2 is an end view thereof.

Figure 3 shows to a larger scale the assembly members connecting the rails of the device to the main track.

The device described hereinafter is adapted to be employed when the line of track is placed upon an embankment, a sectional view of which is shown in Figure 1.

25 1 indicates the rails of the main line of track carried upon the ties 2; 3 indicates the shunting rails of the device permitting a vehicle to be moved off a line of track, these rails being arranged transversely to the track.

The shunting rails 3 are extended in first manipulating rail sections 4 secured between the rails 1 and by second sections 5 secured on the other side of the track.

35 The shunting rails 3 are each provided at one end with a stop 6 while the other end which is adjacent the main track comprises a sheet of metal plate 7 bent in the form of a U-iron, riveted by its base to the sole plate 8 of the rail 3. The front part of the U-iron 7 is cut out in such a way as to enclose partly the profile of the rail 1.

A downwardly turned channel iron 8 is secured by one of its ends by rivets 9 to the 45 side walls of the U-iron 7 and has an upturned channel iron 10 riveted to its other end. To both ends of the shunting rail section 4 is riveted a U-iron 11 of similar shape as the iron member 7. The shunting rail section 5 has its end adjacent the main track

provided with members 7, 8 and 10 in the same manner as the rail 3. The channel irons 10 are provided with slots 12 and the members 11 with slots 13.

In order to assemble the three rail sections 3, 4 and 5 the ballast of the main track will be cleared away underneath the rails 1 at the point where the shunting rails will be erected and then the ends of the said sections 3 and 5 will be pushed from opposite sides underneath the rails 1 into the position shown in Figure 3. The section 4 will be lowered between the rails 1 so that the U-irons 11 slide over the channel irons 8 and 10 as indicated with dotted lines in Fig. 3 and then a key 31 is entered through the holes 12 and 13 to connect the three sections together.

Between the U-irons 7 and 11 and the sole plate or shoe of the rails 1 are interposed wedges 14 which are driven in so as to provide a rigid assembly of the shunting rails with the main track.

The rails 3 are carried by a scaffolding comprising superposed wooden beams 15 supported by supports formed by channel irons 16, one end of which rests upon a flat part of the embankment and the other end of which is supported by posts 17, coupled together by riveted plates 18. Plates 19 are riveted on either side of the channel irons 16 and are provided with a certain number of holes 20 permitting the posts 17 to be secured thereto in different positions by means of pins 21. With their lower ends the posts 17 are carried between two plates 22 each fixed to an angle iron 23, the said plates being also pierced with a certain number of holes 24 permitting the posts 17 to be secured thereto at different heights by means of pins 25. Each angle iron 23 is pivoted at 27 upon a pin secured to plates 30, while it is carried upon a plank 28 situated upon the inclined side of the embankment.

In order to obtain a transverse equilibrium of the supports, the posts 17 are connected together by a cruciform member 29 secured to the plates 14 by means of pins.

On account of the mobility of the posts 17 and the pivotal mounting of the angle plates 10

23, the scaffolding described can be mounted upon slopes of different inclinations.

In order to employ the device described it is necessary for the vehicle to be shunted to include travelling rollers fitting on the rails 3 and for the axles of the vehicle carrying the wheels running upon the main track to be capable of being displaced vertically by means of lifting means of any kind provided upon the said vehicle.

10 It goes without saying that the scaffolding is conditional and that it is limited to points where the track is constructed upon an embankment. The device described may be employed simply with a scaffolding limited to the use of the beams 15 or even without the latter on flat ground.

I claim:

1. A device of the class described, comprising, in combination with a main line of track, 20 a shunting track adapted to be placed transversely to the main track, each rail of said shunting track being divided into a first rail section placed outside the main track and a 25 second rail section placed between the rails of the main track, U-iron shaped members secured to the ends of the shunting rail sections adjacent the rails of the main track, and a channel iron secured to the U-iron member of the first rail section and adapted to extend below the rail of the main track for connection with the U-iron member of said second shunting rail section.

2. A device of the class described comprising, in combination with a main line of track, 35 a shunting track adapted to be placed transversely to the main track, each rail of said shunting track being divided into a first rail section placed outside of the main track and a 40 second rail section placed between the rails of the main track, U-iron shaped members secured to the ends of the shunting rail sections adjacent the rail of the main track, the end of said U-irons facing the rail of the main 45 track being shaped so as to overhang the shoe of said rail, wedges driven between said shoe of the rail and said overhanging parts of the U-irons, and a channel iron secured to the U-iron of the first rail section and adapted to 50 extend below the rail of the main line for connection with the U-iron member of said second shunting rail section.

3. A device of the class described comprising, in combination with a main line of track 55 placed upon an embankment, a shunting track divided into a plurality of sections adapted to be placed transversely to the main track, one of the sections extending horizontally and laterally of the main track to above 60 the inclined side of said embankment, and a scaffolding placed upon said inclined side to support the laterally extending shunting rail section.

4. A device of the class described comprising, in combination with a main line of track 65

placed upon an embankment, a shunting track divided into a plurality of sections adapted to be placed transversely to the main track, one of said sections extending horizontally and laterally of the main track to above the inclined side of said embankment, 70 a scaffolding placed upon said inclined side and including a horizontal member carrying said laterally extending rail section, an inclined member pivoted to said horizontal member and supported by the inclined side of the embankment, a vertical post, and means on said horizontal and inclined members for connection of said vertical post at various points thereof, whereby to adjust the scaffolding to different inclinations of the embankment.

In testimony whereof I affix my signature.

AUGUSTE SCHEUCHZER.
